UNITED STATES PATENT OFFICE.

JOHN D. MILLER, OF WASHINGTON, DISTRICT OF COLUMBIA, ASSIGNOR OF ELEVEN-SIXTEENTHS TO FIRMAN R. HORNER, ALLEN S. JOHNSON, AND JERRY F. RITTER, OF SAME PLACE.

DESIGN FOR A MILK-JAR.

SPECIFICATION forming part of Design No. 31,681, dated October 17, 1899.

Application filed March 3, 1899. Serial No. 707,680. Term of patent 14 years.

To all whom it may concern:

Be it known that I, JOHN D. MILLER, a citizen of the United States, residing at Washington, in the District of Columbia, have invented and produced a new and original Design for Milk-Jars, of which the following is a specification, reference being had to the accompanying drawings, forming part thereof.

Figure 1 is an elevation of a milk-jar according to my new design. Fig. 2 is a top plan view of the same.

As shown in the drawings, the leading or

material feature of my design consists in the top having the flat sides 1 and the dovetail groove 2 in said sides.

Having described my invention, what I claim as new, and desire to secure by Design Letters Patent, is—

The design for a milk-jar as herein shown and described.

JOHN D. MILLER.
